A. DREVENSTEDT

BOX COVER PAPER OR SIMILAR MATERIAL

Filed Jan. 24, 1927

Inventor:
Amy Drevengstedt
by her Attorney,
Norman M. Hinman

UNITED STATES PATENT OFFICE.

AMY DREVENSTEDT, OF NEW YORK, N. Y., ASSIGNOR TO JOHN WANAMAKER NEW YORK, OF NEW YORK, N. Y., A CORPORATION OF NEW YORK.

DESIGN FOR A BOX COVER PAPER OR SIMILAR MATERIAL.

Application filed January 24, 1927. Serial No. 20,481. Term of patent 7 years.

To all whom it may concern:

Be it known that I, AMY DREVENSTEDT, a citizen of the United States, and a resident of New York city, New York, have invented a certain new, original, and ornamental Design for a Box Cover Paper or Similar Material, of which the following is a specification, reference being had to the accompanying drawing, in which the figure is a face view of a box cover paper or similar material, illustrating my new design.

I claim:

The ornamental design for a box cover paper or similar material, substantially as shown.

AMY DREVENSTEDT.
